UNITED STATES PATENT OFFICE.

KUNITOMI OHASHI, OF TOKYO, JAPAN.

APPARATUS FOR TWISTING MIXED FEATHER YARN.

Application filed March 26, 1921. Serial No. 455,778.

To all whom it may concern:

Be it known that I, KUNITOMI OHASHI, the subject of the Emperor of Japan, residing at No. 2145 Sugamo-cho Kita-Teshima-5 gun, Tokyo, Japan, have invented certain new and useful Improvements in an Apparatus for Twisting Mixed Feather Yarn, of which the following is a specification.

This invention relates to an apparatus for 10 twisting mixed feather yarn consisting of a double edged circular cutter secured to the upper one of two shafts which are mounted on two posts of a frame, a circular block secured to the lower shaft below the cutter, 15 and rubber rollers provided one on either side of the cutter and the block, all being so arranged that the barbs of feathers cut off from their shafts by the cutter are inter-twisted in the two threads which run between each pair of the upper and lower rubber 20 rollers. The object of this invention is to obtain a simple apparatus for inter-twisting barbs of feathers in two threads.

The accompanying drawings show an apparatus embodying my invention in which,

Fig. 1 is a side view;

Fig. 2, a plan;

Fig. 3 is a front view of the more important part of the engine, while

Fig. 4 is a perspective view thereof, and

Fig. 5 shows how the barbs cut off from the feathers are intertwisted in threads.

The same reference numbers refer to the same or corresponding parts throughout all 35 the figures.

To explain my invention more fully, reference being had to the accompanying drawings, on a frame there are fixed two posts on which are mounted two shafts 1 and 2 one above the other. At the middle part of the upper shaft 1 is secured a cutter 3 provided with two circular cutting edges with a narrow groove 4 between them, and on either side thereof, a rubber roller 5. 40 On the lower shaft 2 at the middle part below the cutter 3 is secured a circular block 6, also with a rubber roller 7 on either side. Above and below the rollers there are provided four spools, two 13 above and two 13' 45 below, and on the front of the upper and lower rollers there are respectively fixed to the posts two bars 12 and 12'. On the shaft 2 outside of a post a toothed wheel 8' and a rope wheel 9 are firmly secured, the said toothed wheel 8' engaging another toothed

wheel 8 fixed to the shaft 1. On the other end of the same shaft 2 outside the other post, there is fixed a drive wheel 10 and between the drive wheel 10 and the post, a chain wheel 11. From each front post there 60 extends backward a rail 16 to a rear post, and on these rails 16, a carriage 18 travels. To this carriage is secured a bobbin holder with two bobbins 19 mounted thereon. The carriage 18 is a square frame, and within 65 the carriage below the bobbins is a rope 24 by which the operator may move the carriage in one direction by pulling thereon. On a cross piece of the rear posts there is mounted a chain wheel 21, and a chain runs 70 from the rear to the front part of the carriage 18 passing over this chain wheel 21, and then over the chain wheel 11 secured to the shaft 2. On the same cross piece of the rear posts and also the bobbin holder, 75 there are mounted four pulleys 15, two on the former and two on the latter, and a rope runs from the rope wheel 9 over the pulleys 15 of the cross piece, then over one of the pulleys of the bobbin holder, and after going 80 around the bobbins one after another returns back over the other pulley of the bobbin holder. The carriage is brought forward when required by means of the rope 24 tied to the frame 17.

To twist feather yarn with my apparatus, first shift the carriage 18 to the front, bring threads 20 from the spools 13 and 13' over the rods 14 and between rollers 5 and 7, tie them to the bobbins 19, and transmit motion 85 to the drive wheel 10, at the same time feeding the apparatus with feathers by inserting quill part thereof into the groove 4 of the cutter. Then the shaft 2 revolving, the chain 22 will take the carriage 18 rearward 90 and the rope 23 will cause the bobbins to revolve, while the cutter will cut the feathers and the barbs separated from the shafts will be caught between the two threads, and will be intertwisted with them, when the 95 carriage has reached the limit of the rails, stop transmission of motion to the drive wheel, and pull the rope 24. This will bring the carriage forward, at the same time raising the twisted feather yarns over the bobbins and causing them to be wound thereon, because in this case the chain wheel 11 will be revolved in the opposite direction and the rope wheel 9 also will revolve to the opposite direction, so bobbin can wind the 100 105 110

feather yarn. By repeating this process, any required amount of mixed feather yarn can be obtained.

I claim:—

- 5 1. An apparatus for making mixed feather yarn, consisting of a double-edged cutter, a rubber roller on either side above, a circular block, and a rubber roller on the either side below, all being so arranged that
- 10 the threads between which the barbs of feathers cut off by the cutter are caught pass between the rollers and with the feathers are twisted into mixed feather yarn, substantially as and for the purpose hereinbefore set forth.
- 15 2. Apparatus for making feather yarn

comprising thread twisting means, a cutter in advance of the latter, to which feathers are presented and which acts to cut the barbs therefrom, the barbs being delivered 20 to the threads to be intertwined therewith.

3. Apparatus for making feather yarn which comprises a pair of rotary cutters adapted to cut barbs from feathers, duplicate thread-twisting means to each of which 25 a pair of threads is delivered, and to which the barbs cut by the respective cutters are delivered.

In testimony whereof I hereunto affix my signature.

KUNITOMI OHASHI.
